Fig. 3

*Fig. 4**Fig. 6**Fig. 5*

FIG. 1 is a perspective view of the front, top and one side of the dental cup filler;

FIG. 2 is a side elevational view of the dental cup filler, taken from the side opposite that shown in FIG. 1;

FIG. 3 is a front elevational view of the dental cup filler;

FIG. 4 is a rear elevational view of the dental cup filler;

FIG. 5 is a top plan view of the cup dental filler; and

FIG. 6 is a bottom plan view of the dental cup filler. The broken lines are shown for illustrative purposes only.

We claim:

The ornamental design for a dental cup filler, substantially as shown and described.
